UNITED STATES PATENT OFFICE

132,173

DESIGN FOR AN ORONASAL MASK

Walter M. Boothby and William Randolph
Lovelace, II, Rochester, Minn.

Application October 4, 1940, Serial No. 95,630

Term of patent 14 years

To all whom it may concern:

Be it known that we, Walter M. Boothby and William Randolph Lovelace, II, citizens of the United States, residing at Rochester, in the county of Olmsted and State of Minnesota, have invented a new, original, and ornamental Design for an Oronasal Mask, of which the following is a specification, reference being had to the accompanying drawing, forming part of the specification.

Fig. 1 is a front elevational view of an oronasal mask or similar article embodying our new design.

Fig. 2 is a rear elevational view of the mask of Fig. 1.

Fig. 3 is a side elevational view of the mask of Fig. 1.

We claim:

The ornamental design for an oronasal mask, substantially as shown.

WALTER M. BOOTHBY.

WILLIAM RANDOLPH LOVELACE, II.
